LIQUID DISPENSING APPARATUS

Filed July 25, 1925

Linnicus E. Baker

INVENTOR

BY Walter A. Knight

ATTORNEY

UNITED STATES PATENT OFFICE.

LINNAEUS E. BAKER, OF FORT WAYNE, INDIANA, ASSIGNOR TO WAYNE COMPANY, OF FORT WAYNE, INDIANA, A CORPORATION OF INDIANA.

LIQUID-DISPENSING APPARATUS.

Application filed July 25, 1925. Serial No. 46,121.

My invention relates to improvements in liquid dispensing apparatus of the so-called visible type, commonly used for dispensing gasoline. The apparatus has a vertically 5 adjustable tube and belongs to that class of such apparatus in which the adjustable tube is on the delivery side of the pump in contra-distinction to those having an adjustable overflow tube.

10 In apparatus of this type the elevated visible measuring container is provided with a fixed overflow pipe to drain back liquid to the maximum measuring capacity of the container and the movable discharge pipe whereby any portion of the remaining liquid may be accurately drawn off for delivery by adjusting the height of the discharge pipe below the open end of the overflow pipe and thus permitting the discharge 20 of the measured quantity of liquid.

The principal object of my invention is to provide in such an apparatus means for quickly and accurately dispensing the entire number of units of liquid which the apparatus is adapted to contain or any less quantity.

Another object of my invention is to provide a dispensing apparatus in which the visible container is set low to facilitate the 30 reading of the quantity graduations on the container, at the same time having the liquid delivery outlet from the container high enough to permit the rapid and complete draining of the hose into the container of the customer's vehicle. The means employed for accomplishing this is a U-tube and means for preventing liquid being siphoned from this tube on completion of the measure, for such siphoning would give 40 false measure.

In the particular embodiment of my invention selected for illustration

Figure 1 is a dispensing apparatus of the visible type shown in vertical axial section, certain of the pipes being shown in full line, 45 where it is thought that such showing better illustrates the structure, and

Fig. 2 is an enlarged cross section on line 2-2 of Fig. 1 as though shown there in 50 full.

Referring now to the drawings, A is the post portion of the casing resting upon the pedestal A¹ and having at its top a cap A², the three held together by tie rods a in the

usual manner. Upon the pedestal is secured 55 a bracket a¹ in which a quantity stop rod is pivoted and to which a guide rod is secured, as will hereinafter be more fully described.

A glass container B is secured between the cap A² and top plate b by tie rods b¹ in 60 the usual manner. A hand hole cover b² facilitates access to the visible container. The container is provided with the usual quantity graduations as indicated in Fig. 1, the container shown being of five gallon 65 capacity.

A fill pipe C is connected in the usual manner to any suitable pump (not shown) which draws the supply of gasoline or other liquid from an underground storage tank 70 (not shown). At its top the fill pipe C is provided with a deflector cap c which permits quiet filling of the container B to a height above the level of the top of the overflow pipe D, which is fixed in position 75 to drain back excess liquid to the zero graduation on the container B. The overflow pipe D connects with the storage tank in the usual manner.

A vent hole c¹ is provided in the top of 80 the deflector cap to prevent liquid being siphoned out of the visible container B below the zero point upon cessation of pumping.

Into the cap A² is threaded from below 85 one leg E of the U-tube and the discharge tube F is adapted to be vertically adjusted within the tube E through the stuffing box a² to prevent the escape of liquid from the container B around the tube F into the 90 tube E.

At its lower end the tube E is provided with a return bend casting E¹ forming the base of the U and the other leg E² of the U-tube is secured to the member E¹. At the 95 top of the tube E² is secured an L e and a horizontal discharge tube e¹ with any suitable serve valve e² to control the flow of liquid to the customer's car.

At a point beyond the serve valve e² is 100 connected a vent pipe e³ which preferably extends into the free space at the top of the container B, and ensures complete and rapid draining of the hose H.

In line with the center of the pipe E 105 through the bottom of the U, E¹, is an opening with a stuffing box e⁴ through which extends the adjustment rod f which is secured

to the lower end of f^1 of the tube F in any suitable manner, as by fork and rivets as shown.

It will be seen that the tube F is open at both ends so that liquid can freely flow through it from container B down through pipe E across through the return bend E^1 and up through the pipe E^2 and then cross through the valve e^2 to discharge.

10 The adjustment rod f is secured at its lower end to a crosshead f^2 which is raised and lowered by means of the rack f^3 , pinion f^4 and crank f^5 .

A crosshead guide rod f^6 is secured at the bottom to bracket a^1 and at the top to a cross plate a^3 and extends through a hole in the crosshead f^2 .

The height to which the discharge pipe F is adjusted from time to time is controlled 20 by any suitable stop mechanism, as that shown by stop rod G pivoted at the bottom in bracket a^1 and at the top in cross plate a^3 . It is provided with a plurality of individually adjustable stops g fixed to the rod 25 G, and the rod is rotated into suitable contacting position of any predetermined stop g by means of the bevel gears g^1, g^2 and knob g^4 on the shaft g^3 .

I do not intend to limit myself to the precise structure shown but claim as within the scope of my invention any apparatus readable on the claims.

I claim as my invention and desire to secure by Letters Patent of the United States:—

1. A liquid dispensing apparatus having in combination an elevated measuring container for the liquid to be dispensed, a U-tube whose vertical legs are constantly in fluid communication with each other below said container with one vertical leg connected therewith, a discharge pipe open at both ends vertically adjustable within said container and leg, means for preventing the flow of liquid from said container into said

leg except through said discharge pipe, the other leg of said U-tube terminating in an outlet pipe, and means connected with said outlet pipe for breaking the siphon from said U-tube. 50

2. A liquid dispensing apparatus having in combination an elevated measuring container for the liquid to be dispensed, a U-tube whose vertical legs are constantly in fluid communication with each other below 55 said container with one leg connected therewith a discharge pipe vertically adjustable within said container and said leg of the U-tube, a stuffing box in the bottom of the container through which said discharge pipe passes, the other leg of said U-tube terminating in a serve valve and hose connection, and a vent to facilitate the complete and rapid draining of the hose and thus prevent siphoning liquid from the U-tube. 60 65

3. A liquid dispensing apparatus having in combination a transparent elevated measuring container for the liquid to be dispensed, a U-tube whose vertical legs are constantly in fluid communication with each other below 70 said container with one leg connected with the bottom thereof, a discharge pipe open at both ends to form a liquid passage from said container to said leg of the U-tube, an adjusting rod secured to said discharge pipe extending down through a stuffing box in the return bend portion of said U-tube, means for adjusting the vertical height of said discharge pipe by means of 75 said adjusting rod, a stuffing box in the bottom of said container through which said discharge pipe passes, the other leg of said U-tube terminating in a serve valve and hose connection, and a vent to facilitate the complete and rapid draining of the hose and thus prevent siphoning liquid from the U-tube. 80 85

In testimony whereof I have hereunto set my hand.

LINNAEUS E. BAKER.
